DESIGN FOR A HAIRBRUSH

William C. Bird, Northampton, Mass., assignor to Pro-phy-lac-tic Brush Company, Northampton, Mass., a corporation of Delaware

Application May 25, 1940, Serial No. 92,622

Term of patent 14 years

To all whom it may concern:

Be it known that I, William C. Bird, a citizen of the United States of America and a resident of Northampton, in the county of Hampshire, Commonwealth of Massachusetts, have invented a new, original, and ornamental Design for Hair-brushes, of which the following is a specification, reference being had to the accompanying drawing, forming part thereof.

In the drawing:

Fig. 1 is a face view of a hairbrush, showing
my new design,

Fig. 2 is a side view,

Fig. 3 is a back view, and

Fig. 4 an end elevational view taken from the bristle end thereof.

I claim:

The ornamental design for a hairbrush, substantially as shown.

WILLIAM C. BIRD.
